United States Patent Office

Des. 225,430
Patented Dec. 12, 1972

225,430

PLATE

Gerald Gulotta, New City, N.Y., assignor to Block China
Corporation, New York, N.Y.

Filed Dec. 16, 1970, Ser. No. 26,528

Term of patent 14 years

Int. Cl. D7—01

U.S. Cl. D44—15

FIG. 1

FIG. 2

FIG. 3

FIG. 4

FIG. 5

FIG. 1 is a plan view of a plate showing my new design;

FIG. 2 is a side elevational view thereof;

FIG. 3 is an end elevation thereof;

FIG. 4 is a bottom view thereof;

FIG. 5 is a section taken on the line 5—5 of FIG. 1.

I claim:

The ornamental design for a plate, substantially as shown.
